UNITED STATES PATENT OFFICE

JUDSON L. MOORE, OF NEW ORLEANS, LOUISIANA

ROTARY PUMP

Application filed February 25, 1931. Serial No. 518,224.

The invention relates to rotary pumps, and has for its object to provide a device of this kind comprising a casing having eccentrically mounted therein a rotor or cage cooperatively mounted with pivotally mounted vanes, mounted on a stationary shaft, axially with the casing and forming means whereby upon rotation of the cage, said vanes will be rotated for sucking in and discharging fluid between the vanes outside of the cage.

A further object is to provide the cage with rockably mounted bearing members in which the vanes are slidably mounted, and which bearing members extend transversely through the cage.

A further object is to form the rockably mounted bearing members from wedge shaped sections semi-circular in vertical transverse cross section and to provide spring members cooperating with the large ends of the wedge shaped members, whereby they will be moved longitudinally for taking up the wear on the vanes incident to outward and inward movement.

A further object is to provide spring actuated packing blocks between the rockable bearing sections and engaging the opposite sides of the slideable vanes for preventing leakage and for taking up wear on the vanes.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a vertical longitudinal sectional view through the pump.

Figure 2 is a vertical transverse sectional view through the pump showing the rotatable cage in elevation.

Figure 3 is a transverse sectional view taken on line 3—3 of the cage, through one of the rockable bearing members.

Figure 4 is a perspective view of one of the rockable bearing members.

Figure 5 is a perspective view of one of the tapered bearing sections.

Figure 6 is a detail perspective view of a collective kind of one of the side bearing members and its spring.

Referring to the drawing, the numeral 1 designates a casing, and 2 the chamber therein. The lower end of the casing 1 is provided with a base 3, adapted to be mounted on any kind of a foundation. The casing 1, at one side thereof, is provided with an intake port 4, and at the other side with a discharge port 5. Rotatably mounted in a circular depression 6 in the bottom of the chamber 2 is the disc 7 of the cage 8, and it will be noted that said disc is eccentrically mounted within the chamber 2, the purpose of which will presently appear. Extending outwardly from the disc 7, axially thereof, is a drive shaft 9, which may be driven in any suitable manner, however a packing gland 10 is provided for preventing leakage. Formed integral with the disc 7 are concentric arcuately shaped members 11 forming substantially a drum, and which sections 11 are provided with arcuate concentric bearing surfaces 12, which taper transversely of the device for the reception of the tapered rockable bearing sections 13. The ends of the bearing sections 13 extend into bearing openings 14 in the plate 7 and the retaining ring 15 is secured to the ends of the arcuate members 11, as clearly shown in Figure 3. The bearing openings are provided with removable plates 16, which allow ready access to the rockable bearings. Interposed between the plate 16 carried by the disc 7 and the large ends of the tapered bearing sections 13 are expansive coiled springs 17, which cause the wedge shaped bearing members to move longitudinally for taking up any wear developed by the outward and inward movement of the slideable vanes 18.

By referring to Figure 4, it will be noted that the tapered bearing members are collectively round at both ends, in vertical transverse cross section, therefore they will rock in their bearings in the chambers 14, incident to the rotation of the cage eccentrically in relation to the chamber 2 and in relation to

the stationary shaft 19, on which the vanes 18 are hingedly mounted. Disposed between the ends of the rockable bearing sections 13 and within the chambers 14 are packing blocks 20, which engage the sides of the vanes 18 for taking up any wear at these points. 5 Packing blocks 20 are forced inwardly by means of coiled springs 21, therefore it will be seen that they will be held in engagement with the vanes during their longitudinal movement. Springs 17, preferably, extend into apertures 22 in the large ends of the bearing sections 13 for preventing displacement of the springs. It will be noted that a positive rocking bearing is provided for the vanes, which will automatically take up wear as it develops. Vanes 18 are provided with apertures 23, through which air, or fluid will pass for preventing compression of air between adjacent vanes and arcuate members 20 during the rotation of the cage.

Secured to one side of the casing 1 is a cover plate 24, in which is mounted the outer end of the shaft 19 which supports the vanes 18, and said shaft will preferably be prevented from rotation by means of a key 25. By referring to Figure 2, the position of the shaft 19, in relation to the shaft 9, is clearly shown. Retaining ring 15 is secured to the outer ends 30 of the arcuate cage members 11 by means of screws 26.

From the above it will be seen that a rotary pump is provided of the vane type, which is simple in construction, positive in its operation, and one wherein the outer ends of the vanes are slidably mounted in rockable tapered bearing members, formed from registering sections and cooperating with tapered bearing surfaces, said registering sections being under spring tension, whereby wear, incident to vane movement in the bearing members, will be automatically taken up.

The invention having been set forth what is claimed as new and useful is:

45. The combination with a rotary pump comprising slidable vanes slidably mounted in a cage eccentrically and rotatably mounted in a pump casing chamber, of rockable bearing members for said vanes, said bearing members being cylindrically shaped and tapered, said bearing members being rotatably mounted in transverse tapered bearings of the cage, said bearings being formed from tapered segmental sections engaging opposite sides of 50 the vanes, springs within the tapered bearings of the cage at their large ends and forcing said bearing sections longitudinally in the direction of their small ends incident to wear and packing blocks between and spaced inwardly from adjacent ends of the bearing sections and engaging opposite sides of the vanes.

In testimony whereof he hereunto affixes his signature.

JUDSON L. MOORE.
